PAPER CONTAINER FOR FLUID

Melvin H. Sidebotham, West Newton, Mass., assignor to Specialty Automatic Machine Company, Medford, Mass., a corporation

Application October 4, 1935, Serial No. 43,499

2 Claims. (Cl. 93—39.1)

The invention relates to paper receptacles and the manufacture thereof and has particular reference to the production of receptacles for handling measured quantities of fluid, such as milk, to provide economical substitutes for the glass bottles usually employed. It is to be understood however that my improved containers may be employed for holding oil, ground salt, flour and other easy flowing substances.

10 Glass bottles, such as those used for containing milk, are subject to the constant hazard of breakage, besides requiring washing and sterilization at every period of refilling. At the present time, milk bottles are so expensive that a deposit is usually charged for their use, and much care must be exercised in their storage so that the investment represented by the deposit fees will not be lost due to breakage. And there are other well-known objections to the employment of glass bottles for such wide distribution as is necessary to meet the requirements of dairy business.

15 One of the objects of my invention is to produce fluid containers which are not only so economical in cost of production that their preservation after a single use need not be considered, but are also strong enough to stand the usual force employed during handling and transportation whether filled or empty.

20 Another object of my invention is to provide containers which may be stored without waste of storage space; this is accomplished by my containers which are angular in cross-section.

25 Another object is to meet the growing tendency toward scientific household equipment, by providing convenient units for storage in modern electric refrigerators.

30 Another object of my invention is to provide a method of manufacture by which the end closures of a receptacle are sealed by external pressure, without the necessity of a former or tool being used on the inside of the receptacle.

35 With said objects in view, and others herein-after explained, the invention consists in the form and structure and method for the production 40 of the containers substantially as hereinafter described and claimed.

Of the accompanying drawings:

45 Figure 1 is a perspective view of one of my improved containers showing top end closure partly broken away and omitting the cover strip.

Figure 2 is a plan view of the blank which provides the body of the container.

Figure 3 is a top view of the blank shown in Figure 2.

50 Figures 4 and 5 are plan views of the blanks

which provide the top and bottom closures of the container.

Figure 6 is a view similar to the upper portion of Figure 1, and including the cover strip.

Figure 7 is a plan view of the blank which provides the cover strip.

Figure 8 represents a section, enlarged on line 8—8 of Figure 1.

Figure 9 is a plan view of device which may be used in the method for forming and applying adhesive to end closure blank and pressure means for sealing end closures to the body of the receptacle, showing unformed end closure blank in place.

Figure 10 represents a section on line 10—10 of Figure 9 showing unformed end closure blank in place.

Figure 11 represents a partial section on line 10—10 of Figure 9 showing the end closure forming means in position in contact with end closure blank.

Figure 12 represents a partial section on line 10—10 of Figure 9 showing means in operation for applying adhesive to partly formed end closure blank.

Figure 13 represents a section on line 10—10 of Figure 9 showing body structure of receptacle assembled with end closure member and showing means in operation for applying external pressure to secure together said body structure and end closure.

Figure 14 represents a horizontal section below top platform of frame 30 showing operating device for applying pressure to seal end closures of receptacle with body structure.

Figure 15 is an elevation view of partly folded body structure.

Figure 16 is a plan view of partly folded body structure shown in Figure 15.

Figure 17 is an elevation view of body structure 40 folded to flat condition with side portions overlapped.

Figure 18 is a plan view of Figure 17 showing body structure folded to flat condition.

Figure 19 is an elevation view of body structure shown opened to tubular condition.

Figure 20 is a plan view of body structure shown in Figure 19.

Similar reference characters indicate similar parts or features in all of the views.

The body 12 consists of a rectangular sheet of suitably stiff paper or fiber board. As illustrated in Figure 2, it is transversely creased on lines to enable it to be folded to present walls of a body which is square or angular in cross-section. One 50 55

of said walls consists of the overlapping sections 13, 14, the latter having a marginal portion or lip 15 which is off-set from the plane of the body blank as illustrated in Figure 3. Such off-setting is effected prior to folding the blank to tubular form so that, as illustrated in Figure 1, the edge of the section 13 will closely abut, or fit into, the recess between sections 14, 15, resulting from the offsetting of the blank, when said blank is converted to condition to provide the body of the container.

The upper end closure of the container consists of a flat rectangular member 16 having an opening 17 and provided with four marginal portions 18 each of which is widened at its mid-length as indicated at 19 in Figure 4. As also illustrated in Figure 4, the portions 18 are creased to enable them to be snugly folded over and tightly secured to the upper edges of the walls 20 of the body, with the flat area of the member 16 in a plane below the plane of the upper edges of the body, as shown in Figure 1. This is an important feature of my invention as will be explained hereinafter. The purpose of the widened portions 18 will also be explained.

When the material is cut to provide the member 16 (Figure 4) the corner recesses α between the marginal portions 18 are formed somewhat V-shaped. In other words, the adjacent end edges 30 of the members 16, at each corner, are not at a right-angle, but are at an angle somewhat less than 90 degrees. The object of this formation is to provide leak-tight corners at the top, due to the fact that when the marginal portions 18 are folded over the top edges of the walls of the body, the adjacent end edges at α of said portions 18 are crowded tightly together.

The bottom closure of the container is similar to the top one, but has no opening. As illustrated 40 in Figure 5, it comprises a rectangular flat member 20 provided with foldable marginal portions 21 having widened portions 22. And it, also, has recesses α at the corners. And it is secured to the bottom of the body in the same manner as has been described in connection with the top closure.

To close the opening 17 in the top member 16, I provide a strip 23 having one end 24 pointed (Figure 7) and cut near said pointed end to provide a liftable tongue or flap 25. The other end 50 of said strip 23 is cut to provide portions 26, 27 which are creased in right-angular directions so that when applied to position for use (Figure 6) the portions 26, 27 are foldable over the folded portions 18 of the top member at one corner of the latter. To ensure a tight permanent retention of the strip 23 in the position shown in Figure 6, its foldable portion 27 is provided with an extension or tongue 28 which, after the portion 26 has been folded to set position, is then carried 60 over and secured to the outer surface of said folded portion 26.

In some instances it is preferable to fold and form the cover strip to complete condition before 65 assembling it to the top closure.

This securing of the strip to the top of the container where there are three thicknesses of material due to the presence of the over-folded members 18, and at a corner thereof, ensures 70 permanency of position. And owing to the pointed end 24 of the strip extending snugly into a corresponding re-entrant angle, there is practically no liability of the strip becoming displaced from operative position. From this it will be understood that it is important to have the plane

of the closure 16 below the plane of the upper edges of the body of the container.

I have shown in the accompanying drawings a preferred embodiment of my invention, but the form of my improved container may vary, 5 from the form shown, without departing from the spirit of my invention. The container illustrated has a four-sided body structure, but the body structure may be triangular or polygonal in cross-section; also the said body structure 10 may be larger at the bottom than at the top. I have shown a vertical lap-joint as the means for connecting the sides of the body-blank to form the body structure, but any known means may be used to effect the connecting of the sides 15 of said body-blank, without departing from the spirit of my invention.

A preferable way or method to convert the body blank 12 (Figure 1) and the end closure blanks 16 and 20 (Figures 4 and 5) and the cover strip 20 23 (Figure 7) to form and condition to provide a complete container will now be described:

Apply an adhesive to the surface of section 15 of body blank 12 (Figure 2); partly fold sections 13 and 14 of body blank 12 towards each other 25 (Figure 15); complete the folding of said sections 13 and 14 of body blank 12 to a flat condition with section 15 overlapping section 13 (Figure 17); apply pressure to the folded body blank 12 to seal adhesive treated section 15 to section 13; open 30 the folded and sealed body blank 12 (Figures 17) to a tubular condition (Figures 19 and 20). The bottom end closure 20 (Figure 5) is formed and secured to the tubular body structure as follows: The end closure blank 20 is fed to a forming, 35 gluing and sealing device (Figures 9 and 10) having a frame 30 supporting slidable pressure and registering lugs 31, 32, 33 and 34, (Figures 9 and 10). The end closure blank 20 is then acted upon by forming knives 36 (Figure 11) mounted in 40 forming head 35 which is pivotally mounted on pins 39 and 40 supported by frame 30; the forming head 35 is then raised from contact with the end closure blank 20; the head 37, supporting glue applicator 38, is then pivoted about pins 41 and 42, mounted in frame 30, to contact said blank 20 (Figure 12) and thereby deposit glue or other adhesive to the surfaces 21 of said blank 20 (Figure 5); the head 37 is then raised from contact with end closure blank 20; the open end of tubular formed body structure 12 (Figure 19) is then inserted into the adhesively treated recesses formed in end closure blank 20 (Figure 13); the end closure 20 is sealed to the body structure 12 by means of pressure applied externally on said 50 end closure; the sealing pressure is effected by the converging action of pressure members 31, 32, 33, 34 which firmly press the adhesively treated folded sections of end closure blank to the end of body structure 12; the pressure members 31, 32, 33, 34 are controlled by lever 43 (Figure 13) pivoted on pin 44 supported by frame lugs 45; said lever 43 acts through pin 46 on bracket 47 having pins 48 supporting ends of links 49 having pins 50 connected to ends of levers 53 pivoted 60 on pins 51 mounted in frame 30, said levers 53 have pins 52 mounted thereon and connected to pressure members 31, 32, 33, 34.

While means and method are here shown for forming and assembling the bottom end closure 70 with the lower end of body structure, the same means and method may be used to effect assembly of the top closure with the top end of body structure. It is apparent from the above description of the method that both top and bot- 75

tom closures may be formed and assembled with the body structure simultaneously.

In assembling cover strip 23 adhesive is applied to the portions 26 and 27 thereof (Figure 7) said portions 26 and 27 are then folded over the top end closure, as previously described and as shown in Figure 6. In practice no adhesive is applied to the widened areas 19, 22, of the margins of the end closure blanks, because those areas may be utilized for holding and registering during the folding and pressing operations.

To render the container liquid or fluid proof, any suitable treatment may be employed, such as completely coating it with paraffine.

15 To fill the container with milk or other fluid the cover strip 23 may be flexed and lifted sufficiently to expose the opening 17 and the fluid then poured in through said opening. By applying suitable adhesive to the strip 23, it will 20 be retained in place, without risk of becoming displaced. This security of position is due to its being in a plane below the top edges of the body, and to its pointed end 24 entering an angular recess provided by reinforced top edges 25 of the body walls.

Having now described my invention, I claim:

1. The process of making a paper container which comprises the creasing of a rectangular blank, applying an adhesive to a side edge thereof, folding the edges of the blank so that the adhesively treated edge overlaps the opposite edge of the blank, applying pressure externally on the folded blank to permanently seal the overlapped edges thereof, opening the folded 35 blank to tubular condition, forming two rectangular blanks to provide end closures for the body,

said end closure blanks having foldable marginal portions projecting therefrom, the ends of said marginal portions being separated from each other by V-shaped spaces, said V-shaped spaces being formed by making an acute angle cut-out 5 at each corner of the blank, folding the marginal portions to provide recesses, applying adhesive to the recessed portions of the end closures, assembling the end closures to the ends of the body structure and permanently sealing the said 10 ends to the body structure by externally applied pressure.

2. The process of making a paper container, which comprises the creasing of a rectangular blank, applying adhesive to a side portion thereof, 15 folding the edges of the blank so that the adhesively treated edge overlaps the opposite edge of the blank, applying pressure externally on the folded blank to permanently seal the overlapped edges thereof, opening the folded 20 blank to tubular condition, forming a rectangular shaped blank to provide an end closure for the body structure, said end closure blank having foldable marginal portions projecting therefrom, the ends of said marginal portions being 25 separated from each other by V-shaped spaces, said V-shaped spaces being formed by making an acute angle cut-out at each corner of the blank, folding the marginal portions to provide recesses, applying adhesive to the recessed portions 30 of the end closure, assembling the end closure to the body structure by inserting the end of said body structure into the recesses of the formed end closure and applying pressure externally to permanently seal said parts together. 35

MELVIN H. SIDEBOOTHAM.
